UNITED STATES PATENT OFFICE.

JOHN L. SCOTT, OF VICKSBURG, MISSISSIPPI.

CAR-FLANGE-WHEEL OILER.

Application filed January 14, 1925. Serial No. 2,411.

To all whom it may concern:

Be it known that I, JOHN L. SCOTT, a citizen of the United States, residing at Vicksburg, in the county of Warren and 5 State of Mississippi, have invented certain new and useful Improvements in Car-Flange-Wheel Oilers, of which the following is a specification.

This invention appertains to a novel lubricating device and the primary object of the invention is to provide novel means for insuring the correct oiling of the flanges of the front drive wheels of a locomotive under 10 all working conditions.

Another object of the invention is the provision of a novel device for oiling flanges of locomotive drive wheels embodying an oil feed pipe, novel means for supplying oil to the pipe and a novel sliding sleeve for engaging the flange of the wheel associated 15 with the oil feed pipe, the sleeve being adapted to move laterally with the wheel to insure the proper lubrication of the flange.

A further object of the invention is the provision of novel means for automatically 20 supplying oil to the oil feed pipe, said means acting to supply a greater quantity of oil to the sleeve for the flange of the wheel at the outside curve of a curved track than for a straight track and a relatively small quantity 25 of oil to the sleeve of the flange of the wheel on the inside curve of a curved track.

A further object of the invention is the provision of novel means for heating the oil in the lubricator to insure the proper 30 flow of the oil during the cold season.

Another object of the invention is to provide novel means carried by the lower end 35 of the feed pipe and the sleeve for agitating the oil in the pipe and sleeve and for keeping the pipe and sleeve open at all times and free from dirt, grit and the like.

A still further object of the invention is to provide a novel locomotive flange wheel 40 oiler of the above character, which will be durable and efficient in use, one that will be simple and easy to manufacture and one which can be placed upon the market and associated with a locomotive at a comparatively small cost.

With these and other objects in view, the invention consists in the novel construction, arrangement and formation of parts, as will be hereinafter more specifically described, 45 claimed and illustrated in the accompanying drawings, in which drawings,

Figure 1 is a rear elevation of the improved locomotive flange wheel oiler showing the position of the sliding sleeve relative to the flange of a locomotive drive 60 wheel,

Figure 2 is a vertical section through the lower end of the oiler,

Figure 3 is a horizontal section taken on the line 3—3 of Figure 2 looking in the direction of the arrows illustrating the feed nozzle or sliding sleeve.

Figure 4 is a diagrammatic view illustrating the operation of the automatic oil feeding devices, when the locomotive is 70 rounding a curve,

Figure 5 is an enlarged vertical section through the oil supply tank illustrating the automatic oil control feed means,

Figure 6 is an enlarged detail vertical 75 section showing a slightly modified form of the device.

Referring to the drawings in detail, wherein similar reference characters designate corresponding parts throughout the 80 several views the letter A generally indicates the improved locomotive wheel flange oiler and B an ordinary locomotive drive wheel provided with the usual flange 10.

The improved oiler A comprises a supply tank 11 for the oil, which can be of any desired grade and the tank can be of any preferred size or capacity. The upper end of the tank 11 is provided with a removable cover 12 as clearly shown in Figure 5 of the drawing. A depending oil feed pipe 13 communicates with the lower wall 14 of the tank 11 at the central portion thereof and the extreme lower end of the pipe 13 terminates adjacent to the flange of the locomotive drive wheel, which is to be oiled. A head or oil collector 15 is secured to the lower end of the oil feed pipe 13 and is provided with a novel nozzle 16 for supplying the oil directly to the wheel flange. This nozzle 16 embodies a laterally extending downwardly inclined feed pipe 17 and a sliding sleeve 18 mounted thereon. The sliding sleeve 18 is limited in its movement on the feed pipe 17 by means of a screw 19 100 carried by the sleeve 18 and this screw works in a suitable slot or groove 20 formed in the said pipe. As clearly shown in Figure 2 of the drawing the sleeve 18 also extends downwardly at an angle to the horizontal and the outer end thereof is cut so as to extend in 105 the same plane as the flange 10 of the car

100

110

wheel B in order to permit the engagement of the sleeve with the flange at all times. Owing to the inclination of the pipe 17 in the sleeve 18 it is obvious that the oil will be fed by gravity to the flange. It is to be also noted at this point that the pipe 17 is located slightly above the lower wall of the head 15 and when the head 15 is tilted by the locomotive rounding a curved track it can be seen that a greater quantity of oil will be fed to the pipe 17. This of course insures the proper lubrication of the outer rail of the track.

In order to keep the nozzle open at all times to keep the same clear of dirt, grit and the like an agitating rod 21 is loosely mounted within the nozzle and is retained in place by the flange of the wheel. This rod 21 is adapted to be moved back and forth with the nozzle incident to the movement of the car wheel relative to the lubricator and incident to the vibration of the locomotive. This rod will serve as means for carrying dirt and the like out of the nozzle and also insures the proper flow of oil therethrough.

While it has been found that under all normal working conditions that the sleeve 18 will normally engage the flange of the wheel, in some instances it is advisable to provide positive means, such as a spring or the like for forcibly urging the sleeve in engagement with the flange. In some instances, such as in real cold weather, it has been found that the sleeve tends to stick upon the pipe 17.

The lubricator can be held in place on the body of the locomotive in any desired way, and as shown a suitable bracket 22 is connected with the supply pipe 13 and is adapted to be rigidly secured to any preferred part of the locomotive.

Any desired means can be used for regulating the flow of oil through the supply pipe 13, and as shown in the drawing I have provided in connection with the hand controlled means, an automatic means for regulating the oil and this automatic means serves to supply a greater quantity of oil to the flange of the wheel engaging the outer rail of a curved track than the flange of the wheel engaging the inner rail of a curved track.

As shown a partition plate 25 is arranged within the supply tank 11 and covers or houses the upper end of the supply tank 13. The partition 25 directly above the supply pipe 13 is provided with an oil outlet opening 26, the flow of oil through which is controlled by a valve plug 27. This valve plug 27 is automatically operated, as will be later described.

The valve plug serves as means for regulating the flow of oil to the wheel flanges when the locomotive is going around a

curve. The partition 25 at one side of the opening 26 is provided with another opening 28 and the flow of oil through this opening is controlled by a needle valve 29, which can be manually adjusted. As shown the 70 needle valve 29 is threaded through the cover 12 of the oil tank and can be moved toward or away from the opening 28. The oil is adapted to normally flow through the opening 28 to the supply pipe 13 and then 75 to the feed pipe 17 of the nozzle and serves as means for providing a constant flow of oil to the nozzle when the locomotive is running on straight track.

The automatic means for operating the 80 valve plug 27 embodies a lever 30 which is pivotally mounted at a point intermediate its ends on a pivot pin 31 carried by a bracket 32 rigidly secured to the inner face of the cover 12. The lever on one side of 85 the pivot pin 31 has pivotally secured thereto by means of a pivot pin 33 the valve plug 27. The lever 30 on the opposite side of the pivot pin 31 has pivotally secured thereto at 34 the operating rod 35. The operating rod 35 extends through a guide opening 36 in the cover and has resting on the upper end thereof one end of the tilting platform tank 37. The valve plug 27 is normally urged on its seat and the rod 35 95 in engagement with the tilting platform 37 by means of an expansion spring 38 which is wound about a guide rod 39, which slidably extends through the end of the lever adjacent to the valve plug. The spring 38 100 is confined between the cover 12 of the tank and the lever and it is obvious that the spring functions as stated. The tilting platform tank 37 is rockably mounted as at 105 40 to a suitable bracket 41 carried by the cover 12 of the tank. It is to be noted that the tilting platform tank 37 is pivoted adjacent to the rod 35, so that the opposite end of the tank will be at all times, under normally 110 working condition rest upon the stop block 42. This tilting platform is adapted to receive a non-freezing fluid or semi-fluid such as signal oil or mercury, which serves as a weight for tilting the platform tank for a purpose, which will be hereinafter more 115 fully described. The movement of the tank 37 is limited by a set screw 43 adjustably carried by a bracket 44 secured to the cover 12 of the tank 11 and it can be seen that the screw 43 is disposed in the path of one end 120 of the tank 37. When the tank 11 tilts through any cause, the liquid will flow toward the tilted end of the tank and if the tank is tilted to the left, referred to Figure 5 of the drawing, the tank 37 will be 125 rocked on its pivot 40 pushing down on the rod 35 causing the lifting of the valve plug 27 against the tension of the spring 38. This of course allows additional supply of oil to flow into the supply pipe 13.

In use of the improved flange lubricator a lubricating device is disposed on each side of the locomotive so that the front driving wheels on each side of the locomotive will be lubricated. When the engine is operating on straight track the plug 27 will be disposed on its seat and the oil will flow through the opening 28 in the partition down the supply pipe 13 to the nozzle 10 and then to the car wheel flange. When the locomotive is rounding a curve, the same will tilt in view of the inclination of the track which will cause the tilting of the tanks 11 therewith.

It is desirous to convey a greater quantity of oil to the outside rail of the curved track than the inside rail of the track and by referring to Figure 4 of the drawing can be seen the operation of the lubricator. Thus when the locomotive tilts to the left, by referring to Figure 4 of the drawing, it will be seen that the liquid in the tilting platform tank 37 will flow to the left causing the platform on the right to tilt, raising its valve plug 27 and allowing a greater quantity of oil to flow to the supply pipe 13. In view of the fact that the tilting platform of the lubricator on the left in Figure 4 of the drawing rests on the stop block 42 a swinging movement of the platform will be prevented and thus no additional supply of oil is fed to the flange of the wheel on the inner rail of the track.

In actual practice the flow of oil to the flange of the wheel on the inner rail of the track will be cut off in view of the fact that the head 15 carried by the supply pipe 13 will be tilted causing the oil to flow away from the outlet or feed pipe 17 of the nozzle, while the supply pipe 13 on the outside rail will be tilted toward the feed pipe 17 allowing a greater quantity of oil to flow to the nozzle.

In the simplest form of my invention the automatic lubricator can be entirely eliminated and the flow of oil simply governed by the needle valve 39.

In cold climates it is necessary to heat the oil in order to insure the proper flow thereof and to provide for this contingency a steam pipe 46 is provided for the oiler. This pipe includes a coil 45 arranged in the tank 11 about the valve plug 27 and a vertical leg 47, which extends through the supply pipe 13. The pipe 47 extends into a steam chamber 48 arranged around the head 15 and the chamber serves as means for heating the oil therein. A steam outlet nipple 49 communicates with the lower portion of the chamber.

In Figure 6 of the drawing I have shown

a slightly modified form of the invention, in which the lower end of the supply pipe, instead of being provided with the head 15 is provided with a laterally and downwardly inclined extension 50. The downwardly inclined extension 50 of the supply pipe has mounted thereon a nozzle 51 which is of the same construction as the nozzle 18 in the preferred form.

Changes as to details may be made without departing from the spirit or the scope of this invention, but:

What I claim as new is:

1. In a locomotive flange oiler, a supply tank, a depending supply pipe, a laterally and downwardly inclined nozzle carried by the lower end of the supply pipe, means for controlling the flow of oil from the tank to the pipe including a valve plug, a tilting platform tank rockably off the center, means supporting the end of the tank to the greatest distance from its pivot point, an operating lever rockably mounted at a point intermediate its ends, means pivotally connecting the valve plug to the lever at one side of its pivot point, an operating rod pivotally secured to the lever on the other side of its pivot point engaging the end of the tilting platform tank nearest the pivot point thereof, spring means normally urging the valve plug to a closed position, and a movable weight in said tilting platform.

2. In a locomotive flange wheel oiler, a supply tank, a depending supply pipe leading from the lower end of the tank, a laterally and downwardly inclined nozzle carried by the lower end of the pipe, a partition disposed in the supply tank arranged over the supply pipe, manually controlled means for governing the flow of oil to the tank through the partition, and an automatic means for governing the flow of oil through the partition to the supply pipe embodying a movable valve plug, a tilting weight operated platform for actuating said plug, and means for limiting the swinging movement of the platform.

3. In a locomotive flange oiler, a supply tank, a depending supply pipe leading from the tank, a nozzle carried by the lower end of the supply pipe for feeding oil to the flange of the wheel to be lubricated, means for controlling the flow of oil from the tank to the pipe a feed chamber surrounding the point of connection of the nozzle and supply pipe, and a heating pipe extending through the tank and supply pipe and communicating with the feed chamber.

In testimony whereof I affix my signature.

JOHN L. SCOTT.
